Fig. 1

A perspective view of a mechanical assembly. It features a base 15 with a central slot. A horizontal beam 16 is positioned above the base, supported by two angled supports 17. A second horizontal beam 16 is attached to the top of the first, also supported by angled supports 17. The top beam 16 has a rectangular cutout 14 on its right side. The entire assembly is labeled FIG. 3.

UNITED STATES PATENT OFFICE

2,563,700

BEACH PILLOW

Joseph L. Wolf, Tampa, Fla.

Application June 14, 1948, Serial No. 32,947

7 Claims. (Cl. 5—337)

1

This invention relates to a beach pillow for use on sandy beaches and other similar places.

It is an object of this invention to provide an improved beach pillow or supporting device of the kind to be more particularly described hereinafter which may be made from a pair of supporting members pivotally connected together in such a manner that the members will be disposed in an overlying flat abutting relation one to the other in the collapsed position and will be arranged in a manner to provide outwardly divergent supporting surfaces in the extended position thereof.

Another object of this invention is to provide a supporting device of this kind having two pivotally connected members secured together in their pivotal relation by the formation of the connecting members which form integral parts of one or both of the supporting members. No separate pivot pin is required and the separate supporting members provide integral stops for limiting the pivoted movement of the device in the extended position thereof.

A further object of this invention is to provide a beach pillow which is designed to give bathers the utmost comfort while sunning or lounging in the sand. The beach pillow may be made of wood formed from one or two pieces or may be made of plastic or other suitable material.

To the foregoing objects, and others which may hereinafter more fully appear, the invention consists of the novel construction, combination and arrangement of parts as will be more specifically referred to and illustrated in the accompanying drawings, but it is to be understood that changes, variations, and modifications may be resorted to which fall within the scope of the invention as claimed.

In the drawing:

Figure 1 is a front elevation partly broken away and partly in section of the beach pillow constructed according to an embodiment of this invention.

Figure 2 is a top plan view thereof.

Figure 3 is a perspective view showing the device in the collapsed or folded position.

Figure 4 is a fragmentary detailed section showing the dowel connection of one of the panels to the connecting members.

Referring to the drawing, the numeral 10 designates generally a beach pillow or supporting device for use by bathers to support their heads from the sand on a beach. The supporting device 10 is constructed and arranged so that it may be folded and readily stored for transporta-

2

tion and may be extended for use as a beach pillow.

The device 10 is formed of a pair of supporting members 11 and 12 pivotally connected together intermediate the length thereof. The beach pillow 10 may be made from a single piece of wood cut and otherwise worked to the desirable shape and formation or may be made from a plurality of sections securely fixed together. In Fig. 4 of the drawing the supporting members 11 and 12 are shown as formed from a plurality of sections secured together by dowels. The description of either one of the supporting members 11 and 12 will suitably describe the structure of the other as both of the members 11 and 12 are formed in the same manner and arranged in opposition one to the other in the assembly of the device.

The supporting member 12 is formed of a pair of panels 14 and 15 connected together at one end thereof by connecting members 16. The panels 14 and 15 are elongated and flat and are disposed in parallel offset relation one to the other. The connecting members 16 between the panels effect the offset positioning thereof. As the connecting members 16 may be made integral with either one or both of the panels 14 and 15, the structure of the connecting members will be suitably tied in with the initial structure of the supporting member itself. The panels 14 and 15 being disposed in a parallel offset relation one to the other are connected by the members 16 which are disposed at an inclination to the planes of the respective members 14 and 15 thus secured together. The connecting members 16 are secured to the ends of the panels 14 and 15 and are spaced apart along the edges forming a series of grooves as 17 between the connecting members along the adjacent edges of the panels. A portion of one of the edges of each connecting member is formed as a continuation of one of the surfaces of a panel 14 and a portion of the opposite edge of each connecting member may be formed as a continuation of one of the surfaces of a panel 15. The formation between each panel 14 and its companion panel is of sufficient thickness to enable the connecting members 16 to hold said panels in offset relation to each other.

As both of the supporting members 11 and 12 are formed in the same manner the connecting members 16 of each of the supporting members are loosely engaged in the grooves 17 between the spaced apart connecting members of the other supporting member. This connection

provides for the pivotal mounting of the two supporting members 11 and 12. The mounting is a loose one and is not restricted as it would be if a pivot pin were engaged between the two supporting members.

In the drawing the supporting member as 12 is shown as formed of a pair of sections, that is, the upper panel 14 is separate from the lower panel 15. Dowels as 18 are fixed to the ends of the connecting members 16 remote from the edge of the panel 14. The dowels engage in drilled passages 19 in the panel 15 and may be secured by glue or other suitable fastening means.

As shown in Figure 1, the connecting members 16 by having flat surfaces formed as continuations of the surfaces of the adjacent panels of which the connecting members form parts, provide a horizontal flat seating structure as shown in the drawing. As the connecting members 16 have such flat surfaces on both the upper and lower edges, an upper seating surface 20 is formed and a similar seating surface 21 is formed below the connection in the extended position of the supporting members 11 and 12. When the members 11 and 12 are extended to form the cradle, the upper panels 14 are disposed in an upwardly divergent relation one to the other and the lower panels 15 are disposed in a downwardly divergent relation thus forming supporting legs on the structure. The structure may be inverted and the side panels will then be disposed as supporting legs and the difference will only be in the length of the side panels.

When the supporting members are disposed in their extended position, the edges of the panels adjacent the connecting members 16 will abut the edges of the adjacent supporting member along the lines formed by the grooves and connecting members which connect the sections or panels of the supporting members together. In other words, the extension of the supporting members is limited by the engagement of the edges of the panels of the opposite supporting members.

The loose pivotal connection between the supporting members 11 and 12 provides for the disposition of these members in a flat overlying relation for storage or transportation of the device. The connection shown and described will permit the lower panel as 15 of one of the supporting members as 11 to overlie the panel 15 of the other supporting member 12 and the panel 14 at the other end of each of the supporting members will be disposed in this same relation. The flat continuation of the panels 14 and 15 onto the connecting members 16 also forms a continuation of the opposed panels of the opposite supporting members when disposed in overlying flat relation.

I claim:

1. A folding supporting device comprising a pair of supporting members pivotally connected together intermediate the length thereof, each of said members including a pair of flat panels, a plurality of spaced apart connecting members securing said panels together at adjacent ends thereof in offset parallel relation one to the other, the connecting members of one pair of panels loosely engaging between the connecting members of the other pair of panels pivotally connecting said supporting members together whereby one of said supporting members will overlie the other in one position and will be disposed in crossed relation in another position.

2. A supporting device comprising a pair of

supporting members hingedly connected together intermediate the length thereof, each of said members including a first side panel, a second side panel and seat forming connecting members fixed between said panels disposing of said second panel of each supporting member in parallel offset relation to said first panel of the same supporting member, the connecting members of one of said supporting members engaging loosely between the connecting members of the other whereby said first and second panels of one member may be disposed in divergent relation to the panels of the other member in one position and in flat abutting overlying relation in another position.

3. A collapsible supporting device comprising a pair of interengaging supporting members, each of said supporting members including a pair of panels connected together at adjacent ends thereof and disposed in offset parallel relation one to the other, and transversely spaced apart connecting members between the adjacent ends of said panels, the connecting members of each of said supporting members loosely engaging between the connecting members of the other supporting member whereby said supporting members may be disposed in crossed divergent relation in one position and in flat overlying relation in another position.

4. A collapsible supporting device comprising a pair of interengaging supporting members, each of said supporting members including a pair of panels connected together at adjacent ends thereof and disposed in offset parallel relation one to the other, transversely spaced apart connecting members between the adjacent ends of said panels, the connecting members of each of said supporting members loosely engaging between the connecting members of the other supporting member whereby said supporting members may be disposed in crossed divergent relation in one position and in flat overlying relation in another position.

35 5. A collapsible supporting device comprising a pair of interengaging supporting members, each of said supporting members including a pair of panels connected together at adjacent ends thereof and disposed in offset parallel relation one to the other, transversely spaced apart connecting members between the adjacent ends of said panels, the connecting members of each of said supporting members loosely engaging between the connecting members of the other supporting member whereby said supporting members may be disposed in crossed divergent relation in one position and in flat overlying relation in another position, said connecting members including flat surfaces angularly disposed relative to said panels adapted to coact with the connecting members of the adjacent panel whereby the connecting members constitute a horizontal seat between the panels in the divergent crossed position of said supporting members.

40 6. A folding supporting device comprising a pair of supporting members loosely and pivotally connected together intermediate the length thereof, one of said members including a pair of flat panels, and a plurality of transversely spaced apart connecting members securing said panels together at adjacent ends thereof in offset parallel relation one to the other, the other of said supporting members including a pair of flat panels, and connecting means securing said flat panels together at adjacent ends thereof in offset parallel relation one to the other, said connecting means loosely engaging between said connecting members for pivotally connecting said supporting members together whereby one of said supporting members will overlie the other in one position and will be disposed in crossed relation in another position.

45 7. A collapsible supporting device comprising a pair of inter-engaging supporting members, one of said supporting members including a pair of panels connected together at adjacent ends thereof and disposed in parallel offset relation one to the other, and transversely spaced apart connecting members between the adjacent ends of said panels.

els, the other of said supporting members including a second pair of panels and connecting means for securing adjacent ends of said second panels together in offset parallel relation one to the other, said connecting means loosely engaging between said connecting members whereby said supporting members may be disposed in crossed divergent relation in one position and in flat overlying relation in another.

7. The collapsible supporting device of claim 6 in which said connecting members and said connecting means include flat surfaces angularly disposed relative to said first and second panels and adapted to coact with the connecting mem-

bers of the adjacent supporting member to form a flat horizontal seat between the panels in the divergent crossed position of said supporting members.
